United States Patent Office.

HENRY M. PAINE, OF NEWARK, NEW JERSEY, ASSIGNOR TO HIMSELF AND
M. S. FROST, OF NEW YORK CITY.

Letters Patent No. 102,856, dated May 10, 1870.

IMPROVEMENT IN ELECTRO-MAGNETS.

The Schedule referred to in these Letters Patent and making part of the same.

To all whom it may concern:

Be it known that I, HENRY M. PAINE, of the city of Newark, in the State of New Jersey, have invented a new and useful Electro-Magnet; and I do hereby declare that the following is a full and exact description thereof, reference being had to the accompanying drawing, and to the letters of reference marked thereon.

The nature of my invention consists in constructing the legs of the magnet in the form of a sector, (A, Figure 1,) and connecting the same by means of a tie-bolt, (B, Figure 2.)

To obtain the best results the arc should subtend an angle of about thirty-five degrees, and the longest axis of the leg one-fourth in excess of the chord of the arc.

Whatever number of wire may be employed in

clothing the legs, or whatsoever number of coils may be used, the tie-bolt B should be adjusted so as to closely compress the coils together, in order to obtain the full value of the magnet, for, if they be separated, we lose the inductive value of their opposite currents.

What I claim as my invention, and desire to secure by Letters Patent, is—

An electro-magnet whose limbs are substantially sectors or segments, bound together by a tie-bolt, C, and washer, B, in the manner and for the purpose as described.

HENRY M. PAINE.

Witnesses:

GEORGE P. PAINE,
JNO. JONES.
